UNITED STATES PATENT OFFICE.

FRANCIS B. PERKINS, OF ELGIN, ASSIGNOR TO THE ELGIN NATIONAL WATCH COMPANY, OF CHICAGO, ILLINOIS.

MACHINE FOR SPACING WATCH-DIALS.

SPECIFICATION forming part of Letters Patent No. 339,922, dated April 13, 1886.

Application filed August 16, 1881. Serial No. 40,039. (No model.)

To all whom it may concern:

Be it known that I, FRANCIS B. PERKINS, of Elgin, in the county of Kane and State of Illinois, have invented certain new and useful

5 Improvements in Dial-Spacing Machines; and I do hereby declare that the following is a full, clear, and exact description of the same, reference being had to the accompanying drawings, in which—

10 Figure 1 is a perspective view of my machine as arranged for use. Fig. 2 is a plan view of the upper side of the same. Fig. 3 is a side elevation of said machine. Fig. 4 is a vertical central section upon a line passing 15 from front to rear. Fig. 5 is a view of the outer end of the rod used for manipulating the ruling-blades and of the adjustable head employed for holding said blades in position for use. Fig. 6 is a front elevation of the 20 same. Fig. 7 is a plan view of the letter-spacing blades as arranged for use. Fig. 8 is a like view of a dial partially spaced. Fig. 9 is a plan view of the blades employed for spacing the upper and lower ends of the line 25 of letters; and Fig. 10 is a side elevation of my machine, showing a modification in the arm used for carrying the centering-pin.

Letters of like name and kind refer to like parts in each of the figures.

30 The design of my invention is to enable the lines and letters of a watch-dial to be easily, quickly, and accurately made; to which end said invention consists, principally, as an improvement in dial-spacing machines, in a rotatable plate for receiving and sustaining a dial, provided with recesses for the reception of the feet of said dial, in combination with a centering-pin adapted to center the dial and hold the same down upon the plate, sub- 35 stantially as and for the purpose hereinafter specified.

It consists, further, in a dial-spacing machine in which are combined a rotatable plate adapted to receive and sustain a dial, a centering-pin arranged to confine said dial upon said plate, and a spring-actuated pin arranged within the latter and adapted to engage with the seconds-arbor opening in said dial, substantially as and for the purpose hereinafter 45 set forth.

It consists, further, in a dial-spacing ma-

chine in which the locking-pin for engagement with the seconds-arbor opening is made radially adjustable with reference to the dial-supporting plate, substantially as and for the 55 purpose hereinafter shown and described.

It consists, further, as an improvement in dial-spacing machines, in the combination of a rotatable plate for sustaining a dial, provided with recesses for the reception of the dial-feet, a centering-pin adapted to engage with the center opening of said dial and to hold the same down upon said plate, and a spring-actuated pin which is arranged to engage with the seconds-arbor opening of such dial, sub- 60 stantially as and for the purpose hereinafter specified.

It consists, further, as an improvement in dial-spacing machines, in combining, with a centering-pin, trimming-gravers adapted to 70 be swung around and moved vertically upon the same, substantially as and for the purpose hereinafter shown.

It consists, further, in combining with the centering-pin a head which is journaled thereon and provided with a number of gravers having different radial positions, and a spring that is adapted to press said head downward, substantially as and for the purpose hereinafter set forth.

It consists, further, as an improvement in dial-spacing machines, in a rotatable dial-supporting plate provided with means for securing a dial in relative position thereon, and having around its periphery a series of equidistant notches, in combination with a pawl which is adapted to engage with either of said notches and to lock said plate in position, substantially as and for the purpose hereinafter shown and described.

It consists, further, in combining, with the rotatable dial-supporting plate provided with peripheral notches and an engaging-pawl, a pivoted table which furnishes for said plate a pivotal support, and is in turn provided with 95 peripheral notches and an engaging-pawl, substantially as and for the purpose hereinafter specified.

It consists, further, in combining with the rotatable dial-supporting plate fixed guides 100 that are adapted to receive rods for carrying ruling-blades, and to permit the same to move

longitudinally therein, substantially as and for the purpose hereinafter shown.

It consists, further, as an improvement in dial-spacing machines, in a ruling-blade having its scraping-edge arranged longitudinally upon a line which is oblique to the line of motion, substantially as and for the purpose hereinafter set forth.

It consists, finally, as an improvement in dial-spacing machines, in ruling-blades arranged to simultaneously form the upper or the lower ends of a line of letters, substantially as and for the purpose hereinafter shown and described.

15 In the annexed drawings, A represents the base of my machine, which may, if desired, consist of the top of a bench or table. From said base a cylindrical pin, B, projects upward a short distance, and upon the same is pivoted a circular disk or table, C, that has preferably about twice the diameter of the dials to be operated upon. Said table is provided around its periphery with a series of equidistant notches or teeth, c, with which a 20 spring-operated pawl, D, is caused to engage, for the purpose of locking said table in place.

The table C is preferably provided with sixty peripheral notches, corresponding in number to the minute-marks of a dial, but 25 may have such additional number as to correspond to any desired fractional parts of a minute. The pawl D is preferably arranged to move longitudinally upon a radial line, its inner end engaging with the periphery of said table. In order that said table may be easily 30 turned, an annular ring, c', is secured to the upper face of and projects over the edge of the same in convenient position to be grasped by the hand of the operator.

40 Pivoted centrally upon the upper side of table C is a circular plate, E, which has a smaller diameter, and is provided around its edge with notches e, that preferably number two hundred and forty or three hundred, and 45 are engaged by a spring-pawl, F, which enables said plate to be locked in position. The plate E is designed to furnish a support for a watch-dial, G, and is provided with a number of recesses, e', into which the feet g of said dial may be placed. A round pin, e'', having a conical upper end, is arranged vertically within a corresponding recess in said plate, in 50 position to cause its point to correspond to the seconds-arbor opening g' of said dial, and is held in such engagement by the upward pressure of a spring placed beneath.

In order that the machine may be adapted for use with dials having different diameters, and in which the seconds-arbor openings are 55 located at different distances from the center, said pin e'' is made radially adjustable within said plate.

Secured to the base A, and extending upward and inward over the plate E, is an arm, H, which at a point directly over the axis of said plate is provided with an opening, h, through which passes a round mandrel, I, that

is adapted to be moved vertically through said opening, so as to cause its lower pointed end, i, to engage with the central opening, g', of a 70 dial, G, and not only hold said dial down upon said plate E, but also cause the same to maintain a central position thereon.

Journaled upon the mandrel I, below the arm H, is a three-armed spider, K, which is 75 adapted to move vertically thereon, and is held downward with a yielding pressure by means of a spring, i', that is placed between the upper side of said spider and the lower side of said arm. Said spider-arms i' are each provided with a round pin, i'', constructed preferably from wood, which is closely fitted within a vertical opening in said arm, has its lower end pointed and projects downward to an equal distance with the other pins, so as to 80 bear upon the face of the dial G. Said arms may have different lengths, or may have such a number of openings for the reception of a pin, i'', as to enable the latter to be placed at a greater or less distance from the axial center of said spider.

The office of the pointed pins i'' is to define the inner and outer edges of the spacing-lines and the top and bottom lines of the ordinals, for which purpose the portion of said 95 dial which is to contain said lines and ordinals is covered with fusible pigment in a liquid state, and when the same has dried said dial is placed in position upon the plate E and caused to rotate beneath said pins, each of 100 which latter removes said pigment upon a circular line.

Each spacing-line is formed by means of a ruling-blade, L, which is provided within its end with a notch, l, that corresponds to the width 105 of the proposed mark. If said blade is moved across the pigment-coated band upon the dial, it will remove said pigment upon each side of said notch l, while the latter will leave the desired line of pigment adhering to said dial.

In order that the ruling-blade may be easily manipulated and may be moved upon accurately-radial lines, it is secured radially within a cylindrical head, M, which is provided with a reduced rear end, m, that fits into a corresponding axial opening in the end of a round rod, N, and is secured therein by means of two set-screws, n and n', which pass radially inward through said rod, and at their inner ends engage with correspondingly-shaped recesses, m', 115 in said reduced part M.

The rod N when in use is placed within the forked upper end, o, of a U-shaped bar, O, which is secured to the base A in such position as to bring said forked ends in a 125 line with the axis of the plate E. The depth of the notch which forms the outer fork is such as to cause the outer end of said rod to be held at the desired height, while the notch forming the inner fork has such depth as to prevent 130 said rod from resting upon its bottom, and to cause the bearing for the inner end of said rod to be the end of the ruling-blade L. Two washers, n' and n', are placed upon the rod N

in such position that one will impinge against the inner face of the outer forked arm when said rod has reached the desired outer limit of its motion, and the other washer will impinge 5 against the outer face of the inner arm when the inner limit of motion has been reached.

In practice the rod N with the ruling-blade L is moved inward, and then back to its normal position, and the dial G then rotated the 10 desired distance and said operation repeated, such movements being continued until all of the pigment within the limits operated upon is removed, except such as forms the space-lines. Where lettering is to be formed across 15 the face of the dial, a straight band of pigment is placed in the desired position, and the top and bottom lines of the desired letters are formed in the following manner, viz:

Secured to or within a head, M, are two 20 blades, P and P, which correspond in length to the length of the proposed line of letters, and are each provided with notches that correspond in number, position, and length to the upper or lower ends of said letters. Said 25 head M is secured upon a rod, N, that when in use is placed within the forked ends, o, of a bar, O, arranged so that each blade may be moved at a right angle to the line of lettering, and has its longitudinal movement so limited 30 that the blade for operating upon the upper portion of the letters shall not move far enough downward to encroach upon the lower ends of said letters, nor shall the second blade travel over the space occupied by the upper 35 ends of the same.

The operation of the ruling-blades P is to block out vertically the tops and bottoms of the letters, as shown in Fig. 9, after which another ruling-blade, Q, provided with two 40 notches, q, is caused to travel lengthwise of said letters and accurately trim the horizontal lines which constitute the upper and lower ends of the same. The said letters thus blocked out are afterward completed by hand. 45 as indicated by the dotted lines of said Fig. 9. Said ruling-blades P are placed within opposite sides of the head M, and the latter with its rod turned so as to bring either into position for use. It is found that where such can 50 be done a material benefit is derived from arranging the ruling-blades in a line oblique to their movement, in which event the notches within the edges of said blades require to be increased in width in order that the desired 55 width of line may be preserved.

In Fig. 10 is shown a modified form of the arm for carrying the centering-pin. In this modification the arm is shown as consisting of the horizontal plate or bar R, attached to and 60 supported at its rear end by a strong leaf-spring, R', attached at its lower and outer end to the table, as shown, and extending from such attaching-point up and forward. With this form of arm the spider K is placed upon the 65 top of plate or bar R, with its pins i¹ i² i³ extending down below the bar. The center-pin I passes down through spider K and bar R,

and at its lower end is formed precisely like the centering-pin already described. The spring i³ surrounds the pin above the spider, 70 and between it and the head of the pin, so that it presses the spider downward, as does the spring in the form already described and for the same purpose.

Having thus fully set forth the nature and 75 merits of my invention, what I claim as new is—

1. As an improvement in dial-spacing machines, a rotatable plate for receiving and sustaining a dial, provided with recesses for the reception of the feet of said dial, in combination with a centering-pin adapted to center the dial and hold the same down upon the plate, 80 substantially as and for the purpose described.

2. A dial-spacing machine in which are combined a rotatable plate adapted to receive and 85 sustain a dial, a centering-pin arranged to confine said dial upon said plate, and a spring-actuated pin arranged within the latter and adapted to engage with the seconds-arbor opening in said dial, substantially as and for 90 the purpose set forth.

3. A dial-spacing machine in which the locking-pin for engagement with the seconds-arbor opening is made radially adjustable with reference to the dial-supporting plate, substantially 95 as and for the purpose shown and described.

4. As an improvement in dial-spacing machines, the combination of a rotatable plate for sustaining a dial, provided with recesses for the reception of the dial-feet, a centering-pin 100 adapted to engage with the center opening of said dial and to hold the same down upon said plate, and a spring-actuated pin which is arranged to engage with the seconds-arbor opening of such dial, substantially as and for the 105 purpose specified.

5. As an improvement in dial-spacing machines, in combination with a centering-pin, trimming-gravers adapted to be swung around and moved vertically upon the same, substantially 110 as and for the purpose shown.

6. In combination with the centering-pin, a head which is journaled thereon and provided with a number of gravers having different radial positions, and a spring that is adapted to 115 press said head downward, substantially as and for the purpose set forth.

7. As an improvement in dial-spacing machines, a rotatable dial-supporting plate provided with means, substantially as described, 120 for securing a dial in relative position thereon, and having around its periphery a series of equidistant notches, in combination with a pawl which is adapted to engage with either of said notches and to lock said plate in position, substantially as and for the purpose 125 shown and described.

8. In combination with the rotatable dial-supporting plate provided with peripheral notches and an engaging-pawl, a pivoted table 130 which furnishes for said plate a pivotal support, and is in turn provided with peripheral notches and an engaging-pawl, substantially as and for the purpose specified.

9. In combination with the rotatable dial-supporting plate, fixed guides that are adapted to receive rods for carrying ruling-blades and to permit the same to move longitudinally therein, substantially as and for the purpose shown.
10. As an improvement in dial-spacing machines, a ruling-blade having its scraping-edge arranged longitudinally upon a line which is oblique to the line of motion, substantially as and for the purpose set forth.
11. As an improvement in dial-spacing machines, ruling-blades arranged to simultaneously form the upper or the lower ends of a line of letters, substantially as and for the purpose shown and described.

In testimony whereof I hereunto set my hand this 6th day of July, A. D. 1881.

FRANCIS B. PERKINS.
